UNITED STATES PATENT OFFICE

119,053

DESIGN FOR A COMBINED CONTAINER CLOSURE AND SPRAY GUN UNIT FOR COATING MATERIALS OR THE LIKE

Glenn W. Tamm, Chicago, Ill., assignor to
Binks Manufacturing Company, Chicago, Ill.,
a corporation of Delaware

Application December 4, 1939, Serial No. 88,671

Term of patent 7 years

To all whom it may concern:

Be it known that I, Glenn W. Tamm, a citizen of the United States and residing at Chicago, county of Cook and State of Illinois, have invented a new, original, and ornamental Design for a Combined Container Closure and Spray Gun Unit for Coating Materials or the like, of which the following is a specification, reference being made to the accompanying drawing, forming a part thereof.

Figure 1 is a view in side elevation of my new design for combined container closure and spray gun unit for coating materials or the like;

Fig. 2 is a top plan view of the same; and

Fig. 3 is a view in end elevation of the same.

I claim:

The ornamental design for a combined container closure and spray gun unit for coating materials or the like, substantially as shown.

GLENN W. TAMMEN.
